UNITED STATES PATENT OFFICE.

HOWARD J. ATWELL, OF WASHINGTON, DISTRICT OF COLUMBIA.

DESIGN FOR A PENHOLDER AND ENVELOP-OPENER.

SPECIFICATION forming part of Design No. 33,324, dated October 9, 1900.

Application filed September 5, 1900. Serial No. 29,092. Term of patent 14 years.

To all whom it may concern:

Be it known that I, HOWARD J. ATWELL, a citizen of the United States, residing at Washington, District of Columbia, have produced 5 a new and original Design for a Penholder and Envelop-Opener, of which the following is a specification.

The leading feature of this design consists in the design as disclosed by the accompanying illustrations, wherein—

Figure 1 is a plan view of the article embodying the features of the design. Fig. 2 is a similar view of the article in another position.

15 The design is characterized by a cylindrical body 1 of elongated form, having a portion 2 thereof adjacent one end tapered equally in all directions toward a flat projection 3, with

opposite side edges 4 converging toward the outer rounded end 5. The breadth and thickness of the projection 3 are fully within the confining planes of the body 1, and the said projection as an entirety stands away from the body in a central plane.

Having thus described the invention, what 25 is claimed as new is—

The design for a penholder and envelop-opener, herein shown and described.

In testimony that I claim the foregoing as my own I have hereto affixed my signature in 30 the presence of two witnesses.

HOWARD J. ATWELL.

Witnesses:

WM. H. RUPP,
GEO. MAIER.
